US00D691290S

(12) **United States Design Patent**
Carroll et al.

(10) **Patent No.:** US D691,290 S
(45) **Date of Patent:** ** Oct. 8, 2013

(54) **LED-BASED LIGHT BULB WITH MULTIPLE STEMS**

(75) Inventors: **David W. Carroll**, Grantsburg, WI (US);
Wendell Carroll, Minneapolis, MN (US)

(73) Assignee: **Forever Bulb, LLC**, Grantsburg, WI (US)

(**) Term: **14 Years**

(21) Appl. No.: **29/410,217**

(22) Filed: **Jan. 5, 2012**

(51) LOC (9) Cl. **26-04**

(52) U.S. Cl.

USPC **D26/2**

(58) **Field of Classification Search**

USPC D26/1-4; 313/313, 315, 316, 317, 313/318, 493; 315/52, 53, 56, 57, 58
